BALL HOLDING AND BALL RELEASE
MECHANISM

Isadore Edelman, Detroit, Mich.

Application June 25, 1945, Serial No. 601,477

1 Claim. (Cl. 193—40)

1

This application relates to a ball holding and release mechanism for games or the like. Such a mechanism holds balls from rolling down a track, and may be operated by the insertion of a coin into a coin receiver so that the mechanism moves to release the balls which are thereupon free to roll down the track.

The unitary ball holding and release mechanism of my invention is illustrated in the appended drawing. In the drawing,

Fig. 1 is a front view of the mechanism;

Fig. 2 is a top plan view; and

Fig. 3 is a left end view.

The drawing shows a cabinet wall A having a tunnel or track B, whose wall C has an opening D, normally closed by a closure panel 1. Diagrammatically shown at 2 is a ball, which may roll in the track in the direction of the arrow shown. Projecting rearwardly from the panel is a bracket 3 upon which is mounted an electromagnet 4 whose feed wires 5 are connected to a coin controlled switch and an electric current source, not shown, arranged so that upon the deposit of a coin, the switch is closed momentarily so that the electromagnet 4 is energized momentarily.

The magnet has a plunger 10 connected by a wire 11 to a holding bar 12 which normally forms a stop for the ball holding gate 13, holding the ball gate in the position shown, wherein it blocks the movement of the balls in the direction of the arrow. A stop screw 14 limits the movement of the gate in the direction opposite the arrow shown. A tension spring 15 having one end secured to the panel and the other end secured to a rod 16 fastened to the holding bar 12 normally pulls the rod 16 and the bar 12 forwardly on the hinge 17 which mounts the holding bar 12 and it is the tension of this spring that is overcome by the electromagnet 4. When the magnet is energized momentarily, it pulls the bar 12 rearwardly on hinge 17 and the bar releases the gate 13 which thereupon moves rearwardly on its hinge 18 to permit the balls to roll past the gate and the holding bar in the direction of the arrows shown. Since the closing of the switch for the magnet is momentary, as soon as the balls have moved beyond the gate and the holding bar, these are returned to the positions shown by the spring 15.

The panel is provided with several openings 19 permitting the rod 16, the wire 11, and the end 20 of the bar 12 to pass through the panel from the front or track side thereof to the rear or magnet side thereof. The end 20 of the holding bar

2

is formed as shown to provide a stop for the bar 12 under the tension of the spring 15.

It will be observed that in a cabinet or other construction having an opening adapted to be closed by the closure panel 1, the electromagnet portion of the mechanism herein disclosed will be within the closed cabinet and the only exposed portion will be the gate 13 and the holding bar 12.

10 It will also be observed that the unitary mechanism herein disclosed can be inserted into a cabinet and mounted on a portion thereof as a unit merely by using mounting screws 21 for mounting the closure panel 1 in its place on the opening of the cabinet adjacent to the track along which roll the balls.

15 The unitary mechanism may be fabricated and preassembled so that the mechanism as a unit may be mounted in place, by unskilled workers 20 who need only to mount the closure panel by its mounting screws and to connect the feed wires on the magnet to the electrical circuit, which operates that magnet.

25 Similarly, replacement of a mechanism by another, for repair purposes, is a very simple matter, removal requiring only the disconnecting of the wires 5 and the removal of the mounting screws for the panel 1.

30 Now having described the unitary ball holding and release mechanism herein disclosed, reference should be had to the claim which follows.

I claim:

35 A unitary ball holding and release mechanism comprising a panel adapted to be mounted adjacent a ball track, an electromagnet mounted on one side of said panel, a ball holding gate hingedly mounted on the other side of said panel, a gate holding bar hingedly mounted on the gate side of the panel and having a stop portion passing through said panel to engage the magnet side of the panel, a plunger passing through the panel to connect the magnet to the gate holding bar, a rod secured to the bar and passing through the panel to a point near the magnet, and a spring secured to the magnet side of the panel and to the rod at a point near the magnet for normally biasing the bar into gate holding position, said spring being arranged to be overcome upon energization of the magnet which moves the bar out of gate holding position, and a stop for limiting movement of the gate from the ball release position past the ball holding position under bias of the spring, said panel having clearance openings for the stop portion of the bar, for the plunger, and for the rod.

ISADORE EDELMAN.
